Primary Examiner — Kevin K Rudzinski*Assistant Examiner* — Amber J Rabie(74) *Attorney, Agent, or Firm* — Blank Rome LLP(57) **CLAIM**

The ornamental design for a pouch with multiple compartments, as shown and described.

DESCRIPTION

FIG. 1 is a front plan view of a pouch with multiple compartments of our design;

FIG. 2 is a rear view thereof;

FIG. 3 is a top view thereof;

FIG. 4 is a bottom view thereof;

FIG. 5 is a left-side view thereof; and,

FIG. 6 is a right-side view thereof.

The broken lines in the drawings depict portions of the pouch with multiple compartments that form no part of the claimed design.
